GAS OR VAPOR DISCHARGE DEVICE

Application filed January 20, 1927, Serial No. 162,333. Renewed March 28, 1930.

The present invention relates to gas and vapor electric discharge devices and to systems of electrical distribution therefor useful as sources of light, as means for controlling and affecting electrical currents, and useful in the arts generally. And the invention relates to such devices and systems for use on alternating current and wherein the current in each phase is passed between a given set of positive and negative electrodes and in which system means are provided for the prevention of the passage of current between any given set of electrodes except in the designed direction.

Various objects and advantages of the invention will be obvious from the following particular description of one form of apparatus embodying the invention or from an inspection of the accompanying drawing; and the invention also consists in certain new and useful features of construction and combinations of parts hereinafter set forth and claimed.

In the accompanying drawings there is shown for purposes of illustration one form of gas or vapor electric discharge device embodying the invention and a system of electrical distribution for the device and which is also included in the invention.

In the drawing the longitudinal sealed envelope 1 has a purified or conditioned gas or vapor atmosphere which in the present example is mercury vapor supplied from the two spaced apart bodies 3, 3' of liquid mercury which are held in pools and serve therein as cathodes. Near each of said cathodes 3, 3' is a solid anode 8 and 8' which is connected to a coil 10 and 10', respectively, of a few turns in inductive relation to an autotransformer 12. Each of said coils 10, 10' is connected across the filament 14 of a vapor discharge current rectifier 16 and 16' of the tungar type. From the respective plate electrode 18 of each of said rectifiers 16, 16' connection is made through a variable resistance 20 and 20' to an outer end of said autotransformer 12. Current supply mains 22, 22 connect to intermediate points on said coil 12 and connection is made from each of said cathodes 3, 3' in series through an inductance

24 and 24' and a resistance 26 and 26' to a respective side of said auto-transformer coil 12 at a point between an end and the nearest main 22.

As a particular and working example of the embodiment used herein to illustrate the invention the mains 22, 22 are connected across a potential of 110 volts alternating current and the coil 12 is of such design as to give a 310 volt difference between the taps to the resistances 26, 26' and to give a potential difference of 100 volts on the primary of the tungar coupling. The discharge device in the practical example has a fused quartz envelope with a distance of ten inches between each anode and its respective cathode, the power expended in sustaining the main arcs being about 1500 watts. The rectifiers 16, 16' are six ampere tungars well known as such on the market and having definite current carrying and rectifying characteristics. The part of the coil 12 which energizes the coil 10 also applies a potential of 100 volts between each of said anodes 8 and 8' and the cathode 3 which is nearest it and thereby serves to maintain a keep alive arc for each end of the device.

In the use and operation of the device described, upon alternation of current through the device 1 current passes from a given anode 8 in two arc sustaining paths, one to the cathode nearer it with a potential difference of 100 volts therebetween and another to the farther cathode with a potential difference of 310 volts therebetween. The two arcs in each phase contribute as light sources and the shorter arc has the additional function of maintaining the respective mercury pool 3 or 3' in cathode condition. The rectifiers 16, 16' serve to prevent the passage of current from the device 1 by way of the anodes 8 or 8' respectively and thereby prevent their functioning as cathodes.

The inductance 24, is of such characteristic as to cause the current flow from anode 8' to cathode 3 to overlap the current flow from anode 8 to cathode 3 and thereby cause said cathode 3 to have current flowing therethrough at all times during the operation

of the device in a manner well known in the operation of mercury cathode rectifiers of the double or multiple anode single cathode type. The said cathode 3' is likewise kept 5 alive in the other half of the cycle.

The above described embodiment of my invention is useful as a light source for general illumination and also, due to the use of a quartz envelope, the ultra violet rays in the 10 hands of a competent physician can be made use of for therapeutic purposes. Furthermore, if desired, the envelope may be made of heat resisting glass in those cases where it is desired to screen out the ultra-violet or 15 the tube can be of material opaque to light rays.

While I have shown and described and have pointed out in the annexed claims certain novel features of the invention, it will 20 be understood that various omissions, substitutions and changes in the forms and details of the device illustrated and in its operation may be made by those skilled in the art without departing from the spirit of the invention. 25

I claim:

1. A gas or vapor electric device having a closed longitudinal envelope, an anode at each end and a cathode for each anode positioned 30 at the opposite end of said envelope from its respective anode.

2. A gas or vapor electric device having a closed longitudinal envelope, an anode at each end and a cathode for each anode positioned 35 at the opposite end of said envelope from its respective anode, and connected to each of said anodes a gas or vapor device which is conductive only in the direction from its respective anode.

40 3. In a system of electrical distribution a gas or vapor electric device having a closed longitudinal envelope, an anode at each end and a cathode for each anode positioned at the opposite end of said envelope from its respective anode and connected to each of said 45 anodes a gas or vapor device which is conductive only in the direction from its respective anode.

4. In a system of electrical distribution a 50 gas or vapor electric device having an envelope with two anodes and two cathodes therein, one for each anode, a device in series with each of said anodes which is conductive only in the direction from its respective anode, and means for applying a discharge sustaining voltage across respective pairs of anodes and cathodes.

5. In a system of electrical distribution a 55 gas or vapor electric device having an envelope with two anodes and two cathodes therein, one for each anode, means for applying a discharge sustaining voltage across respective pairs of anodes and cathodes, and means in the circuit of each anode conductive of current in a direction toward said

anode but resistant to current passage in the opposite direction.

6. In a system of electrical distribution a 60 gas or vapor electric device having an envelope with two anodes and two cathodes therein, one for each anode, means for applying a discharge sustaining voltage across respective pairs of anodes and cathodes, and a current rectifier in series with each of said anodes permitting current flow thereto.

7. A discharge device, a closed envelope, 65 solid anodes at distant points therein, a gas or vapor filling therein, a cathode for each of said anodes at a distant point therefrom but near another of said anodes, means for applying a normal discharge sustaining potential between each anode and its respective cathode, means for applying a potential less than said normal between each cathode and an anode close to it, and means for resisting 70 a flow of current from the device at an anode under normal potential conditions of the device.

8. In a system of electrical distribution a 75 pair of mains for connecting to a source of electric current supply, an auto-transformer having intermediate points connected to said mains, a vapor arc device having a closed envelope, with two anodes and a cathode for each of said anodes therein, a connection from each of said cathodes through an inductance and a resistance to opposite outer points on 80 said transformer, and a rectifier connected in series between each of said anodes and respective outermost points on said transformer to provide current passage from the transformer to said anode.

9. In a system of electrical distribution, 85 in combination, a gas or vapor arc device comprising a longitudinal container having an anode at each end thereof and a cathode for each anode at the opposite end of the tube therefrom, means for connecting each of said anodes to a source of current, a one way current valve in series with each of said anodes which is conductive in the direction toward the respective anode, and return connection from each of said cathodes to the 90 source of current supply.

10. In a system of electrical distribution, 95 in combination, a gas or vapor arc device comprising a longitudinal container having a solid anode at each end thereof and a cathode for each anode at the opposite end of the tube therefrom, means for connecting each of said anodes to a source of current, a one way current valve in series with each of said anodes which is conductive in the direction toward the respective anode, and return connection from each of said cathodes to the 100 source of current supply.

11. In a system of electrical distribution 105 a pair of mains for connecting to a source of electric current supply, an auto-transformer having intermediate points connected to said

- 5 mains, a vapor arc device having a closed envelope with two anodes and a cathode for each of said anodes therein, a connection from each of said cathodes through an inductance and a resistance to opposite outer points on said transformer, and a rectifier connected in series between each of said anodes and respective outermost points on said transformer to provide current passage from the transformer to said anode, said connections to said transformer being made to apply a potential difference between a given anode and its respective cathode sufficient to maintain a vapor arc therebetween and to apply a potential difference between a given anode and the cathode of another anode sufficient to keep an arc alive from said cathode but not sufficient to break down the negative electrode reluctance of the given anode or of the anode of the last said cathode.

10 12. In a system of electrical distribution, in combination, a gas or vapor arc device comprising a longitudinal container having a solid anode at each end thereof and a cathode for each anode at the opposite end of the tube therefrom, means for connecting each of said anodes to a source of current, a one way current valve in series with each of said anodes which is conductive in the direction toward the respective anode, and return connection from each of said cathodes through a resistance and inductance to the source of current supply.

15 13. In a system of electrical distribution a pair of mains for connecting to a source of electric current supply, an auto-transformer having intermediate points connected to said mains, a vapor arc device having a closed envelope with two anodes and a cathode for each of said anodes therein, a connection from each of said cathodes through an inductance and a resistance to opposite outer points on said transformer, and a rectifier connected in series between each of said anodes and respective outermost points on said transformer to provide current passage from the transformer to said anode, said connections to said transformer being made to apply a potential difference between a given anode and its respective cathode sufficient to maintain a vapor arc therebetween and to apply a potential difference between a given anode and the cathode of another anode sufficient to keep an arc alive at last said cathode.
